(57) CLAIM

The ornamental design for a garment display system, as shown and described.

DESCRIPTION

FIG. 1 is a front right perspective view of a garment display system showing our new design;

FIG. 2 is a front elevation view thereof;

FIG. 3 is a right elevation view thereof; and,

FIG. 4 is a left elevation view thereof.

The broken lines are for the illustrative purposes only and form no part of the claimed design.
